DESIGN FOR A TEXTILE FABRIC

Hyman Blumbaum, Brooklyn, N. Y.

Application August 6, 1938, Serial No. 79,154

Term of patent 3½ years

To all whom it may concern:

Be it known that I, Hyman Blumbaum, a citizen of the United States, residing at Brooklyn, in the county of Kings and State of New York, have invented a new, original, and ornamental Design for a Textile Fabric, of which the following is a specification, reference being had to the accompanying drawing, forming part thereof,

The figure is a plan view of a textile fabric, showing my new design.

The broken lines on the drawing indicate the repeat unit of applicant's design.

I claim:

The ornamental design for a textile fabric, substantially as shown and described.

HYMAN BLUMBAUM.
